UNITED STATES PATENT OFFICE.

ISAAC E. PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT,

COUCH-HAMMOCK.

1,238,697.

Specification of Letters Patent. Patented Aug. 28, 1917.

Application filed July 28, 1914. Serial No. 353,696.

To all whom it may concern:

Be it known that I, ISAAC E. PALMER, a citizen of the United States, and a resident of Middletown, county of Middlesex, and 5 State of Connecticut, have invented an Improvement in Couch-Hammocks, of which the following description, in connection with the accompanying drawings, is a specification, like characters on the drawings representing like parts.

This invention relates to couch hammocks, and particularly to improved means for detachably connecting the frame and the suspension means thereof.

15 In order that the principles of the invention may readily be understood, I have disclosed a single embodiment thereof in the accompanying drawings, wherein:

Figure 1 is a side elevation of a couch 20 hammock having a metallic frame, and provided with my invention;

Fig. 2 is an underneath plan of the hammock shown in Fig. 1;

Fig. 3 is a transverse section plan on line 25 3—3 of Fig. 4;

Fig. 4 is a detail in underneath plan of the construction shown in Fig. 2;

Fig. 5 is a detail in longitudinal section upon the line 5—5 of Fig. 4; and

30 Figs. 6 to 10, inclusive, are views similar to Figs. 1 to 5, inclusive, but representing my invention as applied to a hammock having a wooden or other non-metallic frame.

This invention is an improvement upon 35 that disclosed in my patents Reissue No. 13,282, dated August 15, 1911, and Nos. 1,030,481 and 1,030,487, dated June 25, 1912.

In said patents, I have shown certain 40 means for detachably connecting the frame of a couch hammock and the suspension means thereof, and in said reissue patent, I have broadly claimed a detachable connection for such purpose. In said patents, I have represented hooks secured to the sus- 45 pension means, and engaging the transverse or end members of the frame, the construction being such that by an inward sliding movement of the portion of the suspension means which underlies the frame, the frame and suspension means are disconnected.

In the present application, I have disclosed 50 an improved form or type of detachable connection, and preferably including a pivotal means whereby the parts may be securely locked, and can be disconnected only by ac-

cident to or movement of the suspension ends or means, so that accidental disconnection of said parts is practically out of the question.

Referring more particularly to the drawings, and first to the construction shown in Figs. 1 to 5, inclusive, I have therein represented the couch hammock having a metallic frame. Said frame is herein shown as composed of tubular longitudinal members 1—1, and transverse angle members 2, secured to the tubular members by corner bolts 3, or in any other suitable manner. The said longitudinal and end members of the frame may be made of steel, iron, or other suitable metal. The frame is provided with any suitable seating. For that purpose, I have herein provided metallic links 4, connected in rectangular form to eyes or plates 5. The sides of the seating 60 are preferably connected to the longitudinal members 1 of the frame. For that purpose, I have herein represented short links 6, the ends of which may enter holes in the under side of the longitudinal members 1. Any 65 other suitable lateral connections may, however, be provided. Preferably, the ends of the seating are resiliently connected to the transverse or end members of the frame. For that purpose, I have herein represented 70 75 coiled springs 7.

Any suitable suspension means may be provided. Herein, I have represented cloth or other sheet-like members 8—8, but it is to be understood that the suspension means 90 may be chains, or other strand-like pieces, or any other suitable suspension. The suspension ends are preferably provided at their upper ends with spreaders 9, which are connected by clew-cords 10, with suspen- 95 sion hooks 11 of any suitable character.

Preferably, the lower end of each suspension end or cloth 8 is provided with a transverse end or pocket 12, having therein a spreader 13, which may be of any suitable 100 metallic or non-metallic material. Preferably, however, and as herein represented, I employ a metallic strip or spreader, which is preferably of substantially the full width of the frame.

In order securely to hold or lock the suspension ends together, and yet in such a manner as readily to permit them to be disconnected, I have herein represented at each 105 end of the hammock a plurality of hooks 110

14. I have herein shown each of said hooks as having a looped inner end 15. Each hook is preferably held in position by a bolt 15' passing through the pocket or hem 12, the spreader 13, and the loop 15 of the hook. Underlying each hook is a washer 16, preferably having bent edges 17, so as firmly to press and hold in position the loop 15 of the hook. Upon the threaded portion of each bolt is a securing nut 18. As herein represented, the head 19 of each bolt engages the under side of the transverse angle bar or member of the frame.

15. In order detachably to connect the frame and the hooks, I preferably provide the horizontal web of each angle or end member 2 with a series of holes 20, through one of which the bent end 21 of each hook is adapted to be passed, as represented most clearly in Fig. 3.

16. It will be observed, viewing Fig. 3, that each hook 14 is pivotally connected to one of the end members of the frame, and that in order to disconnect the suspension end 8 from the frame, it is necessary to swing the hooks through substantially 180 degrees. The construction, therefore, is such that normally the hooks are securely interengaged with, or locked with respect to, the end members of the frame, so that it is practically out of the question accidentally to disconnect the suspension ends from the frame. Each suspension end is adapted to be engaged with an end member of the frame by placing the hooks at a position 180 degrees removed from that shown in Fig. 3, inserting the outer ends 21 through the holes 20 in the end members of the frame, and then swinging them into the position shown in Fig. 3. In Fig. 1, I have represented the hammock as provided with a suitable mattress 22, overlying the frame.

17. The construction shown in Figs. 6-10, inclusive, is like that shown in Figs. 1 to 5. In said Figs. 6 to 10, I have represented a hammock having a frame composed of wooden side members 23 and wooden end members 24, suitably secured together by corner screws, bolts, or otherwise. The seating may be of any other suitable character, but I have herein represented it as consisting of a cord 25, reeved back and forth, as illustrated in Fig. 7. The suspension means may be of any suitable character. I have herein represented cloth or sheet-like members 26, preferably similar to the suspension ends 8 of Fig. 1.

18. Instead of providing holes in the end members 24 of the frame, I preferably provide screw-eyes 27, threaded into the inner edge of each end member 24. The construction of the hook is preferably similar to that shown in Fig. 3, and preferably each hook is connected in a similar manner to its suspension end 26. Within the scope of my

invention, the construction may be reversed, and hook means may be provided upon the end members of the frame to be detachably connected in a manner similar to that described with the end or suspension members of the hammock.

19. While preferably, and in order to secure the full benefit and advantages of my invention, I provide the hooks with open ends 21, thus securing a detachable connection between the suspension ends and the frame, I may, under certain conditions, provide means such as hooks with substantially closed eyes, which may be inserted when open through holes in the end members of the frame, or through eyes therein, and then closed, so as to permanently secure the suspension ends and frame together. The pivotal construction of parts in such case would be preserved, but the advantage of the readily detachable connection would be lacking.

20. From the foregoing description, it will be evident that each suspension end is firmly interengaged with, or locked with respect to, the frame, but in such manner as to prevent the parts being accidentally disconnected.

21. Having thus described one illustrative embodiment of my invention, I desire it to be understood that although specific terms are employed, they are used in a descriptive and generic sense, and not for purposes of limitation, the scope of the invention being set forth in the following claims:

1. A couch hammock consisting of a frame, suspension means therefor extending to the under side of the frame, hooks secured to said suspension means and pivotally connected to the frame at the under side thereof, said hooks being adapted to be swung upon their pivotal connections into and from releasing position.

2. A couch hammock consisting of a frame composed of longitudinal and end members, the latter having openings adjacent their inner edges, flexible suspension ends having their lower edges underlying the transverse members of the frame, and hooks connected to said underlying portions of said suspension ends, said hooks having bent ends adapted to be inserted through said openings and then turned through substantially 180 degrees into hammock supporting position.

3. A couch hammock consisting of a frame composed of longitudinal and end members, the latter having openings adjacent their inner edges, flexible suspension ends having their lower edges underlying the transverse members of the frame, and hooks connected to said underlying portions of said suspension ends, said hooks engaging said openings in the end members of the frame.

4. A couch hammock consisting of a frame,

suspension means therefor extending to the under side of the frame, and hooks secured to said suspension means and pivotally connected to the said frame at the lower ends 5 of said suspension means, said hooks being adapted to be swung upon their pivotal connections with said frame into and from releasing position with respect to said frame.

10 5. A couch hammock consisting of a frame having openings 20, suspension means 8 for the frame extending to the under side thereof, hooks 14 secured to said suspension

means 8 and entering said openings 20, said hooks being adapted to be turned with respect to said openings 20 into and from releasing position. 15

In testimony whereof, I have signed my name to this specification, in the presence of two subscribing witnesses.

ISAAC E. PALMER.
